[57] CLAIM

The ornamental design for an electrician's combination tool, as shown and described above.

DESCRIPTION

FIG. 1 is a side elevation of the ornamental design of the present invention, illustrating one side of the tool of which the side opposing the illustrated side is a mirror image thereof with the exception of the portion of the opposing side illustrated in FIG. 2.

FIG. 2 is a side elevation of a portion of the side opposing the side illustrated in FIG. 1.

FIG. 3 is a top view of the ornamental design of the present invention.

FIG. 4 is a bottom view of the ornamental design of the present invention.

FIG. 5 is a rear view of the ornamental design of the present invention.

FIG. 6 is a front view of the ornamental design of the present invention.

Fig. 1.
